UNITED STATES PATENT OFFICE.

ORRA L. GILLILAND, OF SUMMIT, SOUTH DAKOTA, ASSIGNOR TO NATIONAL SHOCK
LOADER CO., OF MINNEAPOLIS, MINNESOTA, A CORPORATION OF SOUTH DAKOTA.

LOADER.

1,272,419.

Specification of Letters Patent. Patented July 16, 1918.

Application filed July 17, 1916. Serial No. 109,628.

To all whom it may concern:

Be it known that I, ORRA L. GILLILAND, a citizen of the United States, residing at Summit, in the county of Roberts and State 5 of South Dakota, have invented certain new and useful Improvements in Loaders; and I do hereby declare the following to be a full, clear, and exact description of the invention, such as will enable others skilled in the art 10 to which it appertains to make and use the same.

My invention relates to improvements in loaders for use in loading bundles, shocks, hay, flax, fodder, manure and the like; and, 15 to this end, generally stated, it consists of the novel devices and combinations of devices hereinafter described and defined in the claims.

In the accompanying drawings, which 20 illustrate the invention, like characters indicate like parts throughout the several views.

Referring to the drawings,

Figure 1 is a fragmentary view of the 25 loader principally in plan, with some parts shown in horizontal section and with some parts shown in different positions by means of broken lines;

Fig. 2 is a right side elevation of the 30 loader;

Fig. 3 is a longitudinal central section taken vertically through the loader;

Fig. 4 is a view in elevation, with some 35 parts sectioned on the line 4—4 of Fig. 2;

Fig. 5 is a detail view, principally in horizontal section taken on the line 5—5 of Fig. 2;

Fig. 6 is a detail view, principally in section on the same line as Fig. 5, but on the 40 opposite side of the loader;

Fig. 7 is a detail view of one of the fork bars, fork-positioning arms and attached chain, some parts being broken away and same parts being shown in section;

Fig. 8 is a left side elevation of the parts 45 shown in Fig. 7;

Fig. 9 is an inside elevation of one of the combined runway and cam plates removed from the machine; and

Fig. 10 is a detail view in section taken on the line 10—10 of Fig. 9.

The numeral 1 indicates a horizontal U- 50 shape main frame, the transverse portion of which forms the rear end of the loader.

This main frame 1 is, as shown, preferably

made from channel bars, the flanges of which are turned horizontally outward. The side members of the main frame 1 are rigidly connected at the center of the loader by a transverse channel tie-bar 2, the flanges 60 of which are turned toward the front of the loader. The side members of the main frame 1 are further connected substantially half way between their front ends and the tie-bar 2 by a transverse channel tie-bar 3, the flanges of which are turned downward 65 to receive an axle 4, which is rigidly secured to said bar by U-bolts 5.

A bearing plate 6 is rigidly secured to the underside of the tie-bar 2, at the transverse center of the loader and projects both forward and rearward therefrom. The tie-bars 2 and 3 are rigidly connected at their intermediate portions by a pair of edgewise spaced bars 7, the front ends of which are 70 directly secured to the bar 3 and the rear ends of which are rigidly secured to the bearing plate 6. In addition to the main frame 1, there is a rear wheel frame 8 and a pair of front wheel frames 9, on which 75 frames 8 and 9 the main frame 1 is supported.

The rear wheel frame 8, like the main frame 1, is U-shape with the transverse portion thereof forming the rear end of the frame 8. This rear wheel frame 8 is relatively narrow and the front ends of its side members are rigidly connected by a bearing plate 10, on which the bearing plate 6 rests. The front end of the frame 8 is connected to 80 the main frame 1 for angular steering movement by a king-bolt 11, passed through a bearing 12 on the back of the tie-bar 2 and alined perforations in the bearing plates 6 and 10. This king-bolt 11 is also extended 85 through a tie-bar 13, which connects the side members of the frame 8 below the bearing plate 10. A draft device 14, to which draft animals may be attached at each side 90 of the loader, is secured to the extreme lower 95 end portion of the king-bolt 11.

Within the main frame 1, is a segmental wearing channel bar 15, the flanges of which are turned toward the front of the loader. The ends of the bar 15 are rigidly secured 100 to the side members of the main frame 1 and the intermediate portion thereof directly engages the rear end member of said main frame and is rigidly secured thereto. This wearing member 15 directly rests on the seg- 110

mental rear end member of the frame 8 and, by reference to Fig. 1, it will be noted that the said rear end member is extended on each side of the frame and to increase the bearing surface on the wearing bar 15 and thereby prevent tilting movement of the main frame 1 on the frame 8.

A single wide traction wheel 16 is located within the frame 8 and has its shaft 17 journaled in bearings 18 on the side members of said frame 8 at the longitudinal center thereof. Angular steering movements are imparted to the traction wheel 16 by a hand wheel 19, an upright shaft 20, drum 21 and a cable 22. The hand wheel 19 is secured to the upper end of the shaft 20 and the drum 21 is secured to the lower end thereof. Upper and lower bearings 23 and 24, respectively, for the shaft 20 are secured, the former to a horizontal member 25 carried by legs 26, and the latter to the rear end member of the main frame 1. The legs 26 are rigidly secured to and project above the main frame 1. The intermediate portion of the cable 22 is wrapped around the drum 21 and the end portion thereof extended in reverse directions and run over guide sheaves 27, journaled on the rear end member of the main frame 1. From the guide sheaves 27, the end portions of said cable 22 are extended toward each other and anchored at 28 to opposite sides of the frame 8.

Each front wheel frame 9 is, as shown, made up of a pair of horizontally spaced angle bars, having journaled therebetween at their front ends a ground wheel 29. The intermediate portions of each pair of these bars are rigidly connected by a bearing 30, and in which bearing is journaled the adjacent projecting end of the shaft 4. Obviously, these bearings 30 connect the front wheel frames 9 to the main frame 1 for vertical swinging movement. The two members of each frame 9, rearward of its bearing 30, are brought together and rigidly connected by a pair of longitudinally spaced bolts 31. The rearmost of these bolts 31 is a long one and extended through a segmental slot 32 formed in the rear end portion of a cast side frame 33, rigidly secured to the respective side member of the frame 1. Spacing thimbles 34 on the long bolts 31 hold the frames 9 properly spaced from the side frames 33 and against horizontal twisting movement. The long bolts 31 and spacing thimbles 34 are sufficiently loose to permit free oscillatory movements of the front wheel frames 9.

The following connections are provided for raising the rear ends of the front wheel frames 9 and securing the same in different vertical positions. On the rear end member of the main frame 1, is a lock segment 35 to which is fulcrumed a foot lever 35^a and a latch lever 35^b located in the same vertical plane, with the latter forward of the former.

A rock shaft 35^c extends transversely of the loader and is journaled in the side frames 33. On the outer projecting ends of this rock shaft 35^c, is a pair of arms 35^d connected to the rear ends of the underlying front wheel frames 9 by short chains 35^e. Also fixed to the intermediate portion of the rock shaft 35^c, is an arm 35^f which extends at an angle to the arms 35^d and is connected to the foot lever 35^a by a long rod 35^g.

The adjustment of the wheel frames 9, of course, raises and lowers the front end of the main frame 1, the purpose of which will hereinafter be set forth. Each wheel frame 9 is connected to the adjacent side frame 33 by a counterweight spring 35^h. Mounted on the rear end of the main frame 1, is an operator's seat 1^a from which the hand wheel 19, foot lever 35^a and latch lever 35^b may be easily manipulated.

A multiplicity of endless traveling pickup forks 36 are mounted at the front of the loader between the side members thereof. Each of these forks 36 comprises a horizontal tubular bar 37 and a multiplicity of laterally spaced curved tines 38 rigidly secured to said bar. Each bar 37 is horizontally supported by a pair of vertically disposed fork-positioning arms 39. These arms 39 have on their inner faces, at the front ends thereof, hubs 40 which are telescoped into the respective bar 37 and rigidly secured thereto by rivets. On the outer face of each arm 39, are horizontally extended front and rear roller-equipped studs 41 and 42, respectively, and a trunion 43, formed by reducing the outer end portion of a horizontally extended stud 44 integrally formed with said arm at the front upper end portion thereof.

By reference to Fig. 7, it will be noted that the trunions 43 are located entirely outward of the roller-equipped studs 41-42 and each axially aligned pair thereof is journaled in bearing lugs 45, integrally formed with certain of the links of a pair of sprocket chains 46 and project thereabove. These sprocket chains 46 hold the forks 36 properly spaced, one in advance of the other, and impart the endless traveling movement thereto.

Rigidly secured to the inner face of each side member of the main frame 1 and the connected side plate 33, is a vertically disposed casting 47. These castings 47 are of irregular shape and project rearwardly and upwardly from the front end of the loader. At the marginal edge of each casting 47, is a laterally or inwardly projecting flange 48 continuous throughout its entire length, with the exception of a passageway 49 at the extreme upper end of said casting. These flanges 48 afford therewithin endless runways 50 for the chains 46. The central portion of each plate 47, within its runway 50, is laterally offset toward the longitudinal center of the loader and has formed therein

cam surfaces 51, 52, 53, 54, 55, 56, 57, and 58. The cam flanges 52 and 54 afford a cam channel 59. The cam flange 56 and the rearward portion of the cam flange 57 afford a 5 cam channel 69 and the cam channel 61, at the junction of the cam channels 59 and 60, is located between the cam flanges 53 and the forward portion of the cam flange 57.

Each sprocket chain 46 runs over lower 10 and upper sprocket wheels 62 and 63, respectively, and relatively large and small guide sprocket wheels 64 and 65 respectively. All of these sprocket wheels are located in the respective runways 50. The sprocket 15 wheels 62 are located at the lower extremities of the castings 47 and their shafts 66 are mounted in said castings. The sprocket wheels 64 are located forward and slightly below the sprocket wheels 63 and their 20 shafts 67 are mounted in the castings 47. The sprocket wheels 65 are located rearward of the sprocket wheels 62 and slightly thereabove, with their shafts 68 mounted in the castings 47. The sprocket chains 46 run 25 over the sprocket wheels 64 and under the sprocket wheels 65. Shafts 69, on the inner ends of which the sprocket wheels 63 are fixed, extend through coincident horizontal slots 70, formed in the side frames 33 and 30 castings 47, with their intermediate portions journaled in bearings brackets 71.

These bearing brackets 71 are mounted on horizontal flanges 72 integrally formed with the outer faces of the side frames 33 and are 35 secured thereto in different horizontal adjustments by bolts 73, extended through slots 74 in said bearing brackets and having screw-threaded engagement with the flanges 72. Obviously, these bearing brackets 71 afford 40 chain tighteners for the sprocket chains 46.

Limited vertical oscillatory movements are imparted to the fork-positioning arms 39, for the purpose of changing the position 45 of the tines 38, by the roller-equipped studs 41 and 42 traveling in the cam channels 59, 60, and 61 and subject to the several cam surfaces, heretofore identified. The relation of the roller-equipped studs 41 and 42 with the 50 cam channels and flanges will be more fully set forth under a brief description of the loader, which will presently be described.

The sprocket chains 46 are independently driven from the traction wheel 16 by the 55 following connections:

Rigidly secured to the left hand hub of the traction wheel 16, is a large sprocket wheel 75 over which and an alined sprocket wheel 76 runs a sprocket chain 77. The sprocket 60 wheel 76 is relatively small and is keyed for rotation in a shaft 78, which extends parallel to the axis of the traction wheel 16 and is journaled at its ends in a pair of bearings 79 on the front end portion of the frame 8. Secured to the shaft 78 for rotation there-

with, is a chain wheel 80, which is alined with a chain wheel 81 keyed to the intermediate portion of a long shaft 82, which extends parallel to the shaft 78 and is journaled in the cast side frames 33. A crossed 70 chain 83 runs over the alined chain wheels 80 and 81 and is held against lateral displacement therefrom, during the steering movement of the traction wheel 16 by a pair of vertical guide rollers 84 journaled on the 75 bar 2. Fixed on each end of the shaft 82, outward of the frame 1, is a relatively large sprocket wheel 85 alined with a relatively small sprocket wheel 86, keyed for rotation with the overlying shaft 69. A sprocket 80 chain 87 runs over each pair of alined sprocket wheels 85 and 86. Also keyed to each shaft 69, outward of the respective sprocket wheel 86, is a miter gear 88 which meshes with a miter gear 89, secured to a 85 shaft 90 for rotation therewith, but with freedom for axial sliding movement thereon. The shafts 90 extend at right angles to the shafts 69 and are journaled in bearings 91 integrally formed with the brackets 71 90 and in bearings 92 on the cast side frames 33. By the above described driving connections, the sprocket chains 46 are caused to travel in a direction to carry the forks 36 on the lower run thereof downwardly and 95 forwardly and the forks on the upper run thereof backwardly and upwardly.

At the forward end of the loader, is an upwardly and rearwardly inclined deck 93 made up of a multiplicity of horizontally 100 spaced members, between which the tines 38 of the forks work throughout part of their traveling movement. The lower end portion of the deck 93 is bent downwardly and rearwardly to a point directly under the 105 sprocket wheels 65 and the upper end portion of said deck is bent rearwardly and downwardly and is supported at its highest point or crown by an angle bar 94. The angle bar 94 is rigidly secured at its ends to 110 side boards 95 which, in turn, are rigidly secured to the main frame 1 and side frames 33. Each member of the deck 93 comprises a pair of laterally spaced angle bars 96 and a flat plate 97 riveted or otherwise rigidly secured to the inturned horizontal flanges thereof and which plates form the top surface of the deck 93. The lower ends of the angle bars 96 of each pair are drawn together and rigidly connected to the channel bar 3 by a metal strap 98.

The tines 38 pick up the bundles Z and carry the same upward nearly, but not quite, to the highest point of the deck 93. The next following bundle or bundles are relied 125 upon to carry or shove the uppermost bundle over the crown of the deck 93, from whence the same will slide or roll downwardly and rearwardly onto the carrier section of a combined carrier and elevator. 130

This combined carrier and elevator is arranged to travel transversely of the loader and deposit the bundles into a rack or box on a vehicle, not shown, driven at one side of the machine.

The combined carrier and elevator comprises a pair of sprocket chains 100 and a multiplicity of transverse slats 101 made from angle bars, with their ends secured to 10 said chains. Each chain 100 runs over a pair of sprocket wheels 102 and 103 and the upper section thereof runs under a guide roller 104 and the lower section thereof under a sprocket wheel 105. The shafts on 15 which the pairs of sprocket wheels 102 and 103 are secured are journaled in adjustable bearings 106 and fixed bearings 107, respectively. The bearings 106 are secured to the outer end of a carrier frame 108 and the 20 bearings 107 are secured to the outer end of an elevator frame 109. This frame 109 is pivoted on the shaft of the sprocket wheels 105 for vertical swinging movement.

The elevator frame 109 is raised and lowered and supported in different oblique positions by a cable 110 secured at one end to a pair of branch rods 111 pivotally attached, one to each side member of the elevator frame 109, near the upper end portions 30 thereof. The other end of the cable 110 is attached to and adapted to be wound upon a windlass drum 112, journaled in a bracket 113 secured to and projecting above the left hand pair of legs 26. A suitable pawl and 35 ratchet device, not shown, will, in actual practice, be provided for holding the windlass drum 112 where set. The cable 110 runs over guide sheaves 114 and 115; the former is journaled in the upper end of the 40 bracket 113 and the latter is journaled on the upper end of an A-frame 116 rigidly secured to the right hand end of the carrier frame 108.

The carrier frame 108 is made up of upper 45 and lower pairs of angle bars having their vertical flanges turned upward and their horizontal flanges turned inward to afford supports over which the chains 100 travel. The guide rollers 104 and sprocket wheels 50 105 hold the chain 100 onto the horizontal flanges.

The bundles Z, indicated by broken lines in Fig. 8, during their upward movement on the deck 93, are held against endwise dis- 55 placement by the upwardly and outwardly inclined side boards 95. The left hand side board 95 is extended rearwardly completely across the frame 108 to prevent the bundles from falling off from the left hand end of 60 the carrier. At the rear side of the carrier frame 8, nearest the rear end of the machine, is a side board 17. This side board 17 and the rear end portion of the deck 93 are so arranged that their lower longitudinal edge portions overlap the upper run of 65

the chains 100 and terminate close to the ends of the slats 101.

The upper run of the combined carrier and elevator travels over a deck 118 secured to the horizontal flanges of the upper pair 70 of angle bars of the frame 108 and a deck 119 secured to the frame 109. A brace rod 120 extends between the carrier frame 108 and the rear end portion of the main frame 1. The combined carrier and elevator is 75 driven by a sprocket chain 121, which runs over aligned sprocket wheels 122 on the shaft 90 and the shaft for the sprocket wheels 103. It will be noted that the shaft 90 is axially aligned with the shaft on which the sprocket 80 wheels 105 are secured.

The operation of the improved loader may be briefly stated as follows:

As previously stated, the chains 46 of the pickup device travel in the endless runways 85 50 and are driven from the traction wheel 16 through the several connections, heretofore identified. During the first part of the lower run of the pickup device, all of the studs 41 and 42 travel in the lower section 90 of the runways 50 and the tines 38 are held in substantially horizontal positions and project in the direction of travel of the loader. In the latter part of this run of the pickup device, the free upper ends of the 95 arms 39 are rocked forward by the engagement of their lower extremities with the flanges 48 and the pull of the chains 46. This rocking movement of the arms 39 carries the studs 42 into the cam channels 60 100 and the studs 41 into engagement with the cam surfaces 58. In this position of the arms 39, the free ends of the tines 38 of a given fork are held downward and have a substantially parallel movement with the 105 ground to pick up a bundle in the path of movement of the improved loader. Under the continued forward movement of the tines 38, the studs 42 enter the cam channels 61 and move toward the forward ends thereof, until the studs 41 have passed the rounded ends, which connect the cam flanges 51 and 58.

After the studs 41 have passed these rounded ends, the arms 38 are moved endwise in an upward and rearward direction and the tines 38 are oscillated to lift their free ends and carry a picked up bundle onto the deck 93. During the upward run of the pickup device, the studs 41 travel in the upper sections of the runways 50 and the studs 42 pass from the cam channels 62 into the cam channels 59. In the latter part of the upward and rearward traveling movement of the tines 38, they are further oscillated 120 to carry their free ends into still higher or releasing positions from the bundle held thereby and, at the same time, they are endwisely withdrawn from said bundle and from between the members of the deck 93. 130

Before the held bundle is entirely released by the tines 38, the previously picked up bundle is shoved or lifted over the crown of the deck 93, from whence it rolls or slides 5 onto the carrier section of the combined carrier and elevator. During the limit of the upward travel of the pickup devices, the rear ends of the arms 39 extend into the passageways 49 and the front ends thereof follow the chains 46 around the sprocket wheel 63 and into the lower section of the runway 50. From the carrier, the bundle is delivered 10 to the elevator section of said combined carrier and elevator and deposited thereby into the rack or box on a wagon driven at 15 one side of the loader. The above described traveling and oscillatory movements of the pickup devices are such that the grain will be picked up and delivered to the combined carrier and elevator without shelling the 20 same.

The operator, during the forward traveling movement of the loader, can, by means of the foot lever 35^a, raise and lower the 25 front end of the main frame 1 to carry the lowermost fork 36 above the obstructions in the field, such as uneven places, stones and stumps, and also to facilitate the picking up of a bundle. The movements of the foot lever 35^a are entirely independent of the 30 latch lever 35^b and when released, the front end of the loader will assume its normal position under its own weight. If it is desirable to set the front end of the loader at 35 a higher altitude than that shown in the drawings, the latch lever 35^b may be pulled toward the operator and secured in any one of the several notches in the lock segment 35. This movement of the latch lever 35^b 40 will pick up the foot lever 35^a and carry the same with it. The flexible connections 35^c permit the front end of the loader to lift, in case the lowermost pickup fork engages and slides over any obstruction in the field, thus 45 avoiding breaking any of the parts of the loader.

While the invention has been illustrated and described as picking up bundles, the same is intended for general use as a loader, 50 as stated in the first paragraph of the specification.

What I claim is:

1. In a loader of the kind described, the combination with a truck, of a plurality of 55 fork bars, means connecting the fork bars and causing the same to move in an endless course, said means including cam-actuated devices for bodily moving the fork bars transversely of the endless course they travel, and pickup forks carried by the fork bars.

2. In a loader of the kind described, the combination with a truck, of a pair of endless chains mounted on the truck and means for driving the same, opposite pairs of cam- 65 actuated arms pivotally secured to the

chains, a plurality of fork bars secured to the arms at points offset from their pivotal connections with the chains, and pickup forks carried by the fork bars.

3. In a loader of the kind described, the combination with a truck having side plates with cam surfaces and wheels, of a pair of chains arranged to run over the wheels, a plurality of opposite pairs of arms having one of their ends pivotally attached to the 75 chains, studs on the other ends of the arms and engaging the cam surfaces on the side plates, a fork bar rigidly connected to each pair of arms at their intermediate portions, and a plurality of pickup forks carried by 80 each fork bar.

4. In a loader of the kind described, the combination with a truck having side plates with cam surfaces and wheels, of a pair of chains arranged to run over the wheels, a 85 plurality of rearwardly projecting pairs of arms having their forward ends pivotally attached to the chains, studs on the rear ends of the arms and engaging the cam surfaces on the side plates, a fork bar rigidly connected to each pair of arms at their intermediate portions, and a plurality of pickup forks carried by 90 each fork bar.

5. In a loader of the kind described, the combination with a truck having side plates 95 with cam surfaces and wheels, of a pair of chains arranged to run over the wheels, a plurality of opposite pairs of arms having one of their ends pivotally attached to the chains, studs on the other ends of said arms 100 and engaging the cam surfaces on the side plates, a fork bar rigidly connected to each pair of arms at their intermediate portions, and a plurality of pickup forks carried by each fork bar, said cam surfaces and studs 105 arranged to constantly hold the arms with the pickup forks in forwardly projecting positions during the travel of their endless course and for bodily oscillating the fork bars independent of the movement imparted 110 thereto by the chains.

6. In a loader of the kind described, the combination with a truck having side plates with cam surfaces and wheels, of a pair of endless chains arranged to run over the 115 wheels, a plurality of horizontal fork bars having arms rigidly secured to their ends, a multiplicity of horizontally spaced and forwardly projecting pickup forks on the fork bars, said arms being eccentrically secured 120 to the chain with respect to the fork bars, and studs on the arms and engaging the cam surfaces on the side plates, said cam surfaces, studs and arms arranged to impart bodily oscillatory movement to the fork 125 bars independent of the movement imparted thereto by the chains.

7. In a loader of the kind described, the combination with a truck having side plates with an endless runway and cam surfaces on 130

each thereof, and wheels journaled in said runways, of a pair of endless chains mounted in said runways and arranged to run over the wheels, a plurality of horizontal fork bars having at their ends arms, a multiplicity of horizontally spaced and forwardly projecting tines rigidly secured to the fork bars, said arms being eccentrically secured to the chains with respect to the fork bars to permit limited vertical oscillation.

tory movement of the arms, and studs carried by the arms and having engagement with the cam surfaces for positioning the tines.

In testimony whereof I affix my signature 15 in presence of two witnesses.

ORRA L. GILLILAND.
